COPYHOLDER

Frank L. Paul, New York, N. Y.

Application February 1, 1939, Serial No. 254,001

2 Claims. (Cl. 120—30)

This invention relates to copyholders and it is a particular object of the invention to provide an improved copyholder that may be used by stenographers, Linotype operators, public speakers, or the like for supporting manuscripts and similar documents and papers in convenient position to be read or copied.

I am aware that copyholders have been used prior to my invention. However, many copyholders heretofore employed have been of cumbersome, expensive construction, or were difficult or inconvenient to operate, or had many intricate moving parts which were subject to wear and would get out of order.

It is an object of the invention to overcome the difficulties heretofore encountered and to provide an improved copyholder of relatively simple and inexpensive construction, which is easy and convenient to operate and has relatively few moving parts so that it may be used for a long period of time with comparative freedom from wear.

It is a further object of the invention to provide a copyholder of the above character which may be readily adjusted as to height or as to the angle at which the manuscript or other document is supported.

For a fuller understanding of the invention reference should be had to the accompanying drawing, in which—

Fig. 1 is a perspective view of a copyholder embodying my invention;

Fig. 2 is a detailed partially fragmentary view of the upper portion of the copyholder, showing in detail the copyholding frame;

Fig. 3 is a plan view of the copyholder;

Fig. 4 is a sectional view in the direction of the arrows on the line 4—4 of Fig. 1;

Fig. 5 is an end view of the copyholding frame from the right-hand end as viewed in Fig. 1;

Fig. 6 is a sectional view in the direction of the arrows on the line 6—6 of Fig. 2; and

Figs. 7 and 8 are end views similar to Fig. 5, showing two modifications of my invention in which releasable locking devices are employed for holding the copyholding rollers in spaced relation.

My improved copyholder comprises a stand 10, and a copyholding frame 11 which is supported on the stand so that it may be adjusted both as to height and as to the angle at which the manuscript is displayed. The stand comprises a base 12 which is of such proportions and weight as to afford adequate support to the copyholder, a tubular standard 13 extending upwardly from the

center of the base, and a collar 14 formed at the top of the standard and provided with a set screw 15.

A rod 16 is disposed in the tubular standard 13 forming telescoping engagement therewith so as to provide for vertical adjustment of the copyholding frame. By means of the set screw 15 the rod 16 may be releasably held in any desired adjusted position. The upper end of rod 16 is bent at right angles, providing the horizontally disposed portion 17, to which the copyholding frame is secured so that it may pivot with respect thereto by means of the metal loop or strap 18 which extends over the portion 17 and is secured to the back of the frame in some suitable manner 15 as by means of the screws 19.

It will thus be seen that the rod 16 may rotate or pivot with respect to the standard 13, and that the frame may pivot or rotate with respect to the horizontal portion 17 of the supporting rod 16. I accordingly provide means whereby the copyholding frame may be pivotally adjusted around both horizontal and vertical pivots.

Adjacent the extreme end of the horizontal portion 17 of the supporting rod I may provide suitable means for preventing the accidental disengagement of the parts at this point, such as the screw or bolt 20, threaded to an aperture provided transversely of the rod and which may be firmly held in position as by means of a lock nut 21. In addition to preventing the parts from becoming disengaged at this point the bolt or screw 20 also serves as a stop so as to confine the pivoting of the copyholding frame around its horizontal axis within predetermined limits. It 35 will be appreciated that when the frame is pivoted to the extreme limits it engages one or the other ends of the screw and is prevented from pivoting beyond that point.

To hold the copyholding frame in adjusted position with regard to its horizontal pivot I may also provide a set screw 22 threaded to an aperture formed through the back of the copyholder so that the end of the screw can engage the horizontal portion 17 of the supporting rod. A lock nut 23 may also be provided in connection with the set screw 22 to hold it firmly in position.

The frame 11 is preferably formed of a flat backing strip of metal or any other desired material as indicated at 24, the ends of which are bent forwardly at right angles so as to form the spaced parallel end portions 25. Supported between the two end portions 25 I provide a pair of copyholding rollers 26 and 27, one of which, namely, roller 26, may be smaller than the other 55

roller, and while it may be rotated with respect to the frame, is held against shifting. The roller 27, on the other hand, is mounted in the frame so that it can rotate and also can shift with respect to the other roller, so as to permit of the convenient insertion of a manuscript or other papers between the rollers.

While the type of roller may be varied, I have found that the illustrated type of roller and roller mounting produces very satisfactory results. Thus roller 26 is formed of a tubular member 28 having a cover 29 made of some suitable friction material such as rubber. The roller is held in position as by means of stub shafts comprising screws 30 and 31 which pass through the end portions of the frame and are disposed inside the tubular members 28. For a purpose which will hereinafter be explained the screw 31 projects a short distance beyond the end of the frame as shown most clearly in Fig. 2. Roller 27 is also formed of a tubular member 32 having a cover 33 made of friction material such as rubber and it is held in position as by means of stub shafts 34 and 35 which are provided with knarled handles 36 at the ends thereof.

So as to provide for shifting of the roller 27 the end portions 25 are provided with elongated, slotted openings 37 through which the stub shafts 34 and 35 extend. The slotted openings are of sufficient length to permit the roller 27 to shift from a position in which it engages as the roller 26 to a position in which it is spaced from the roller.

To normally hold the rollers in engagement with each other I provide a spring 38 on each end portion 25 of the frame. The springs 38 are disposed around machine screws or similar supports 39 and at one end they are anchored against the screws 40, while the other ends thereof engage the stub shafts 34 or 35 which support the roller 27, thereby urging it into engagement with the roller 26.

I also provide convenient means whereby the roller 27 may be shifted away from the roller 26 to facilitate the insertion of a manuscript or other papers. This means preferably comprises a rod 41 extending between and pivotally supported by the end portions 25 of the frame. One end of the rod, i. e., the right hand end as viewed in Figs. 1 and 2, is bent downwardly at right angles to the remainder of the rod, forming a handle portion 42. The handle portion depends downwardly in front of the stub shaft 34 and is adapted to engage the stub shaft when pressure is applied to the handle, so as to cause the shaft and roller to shift. Connected to the opposite end of the rod 41 is a depending member which may take the form of a screw 43, which is adapted to engage the stub shaft 35 in a similar manner so as to cause the roller to shift evenly when pressure is applied to the handle 42.

So as to facilitate operation of the handle I preferably provide a relatively fixed handle 44 which is attached to the rear of the frame and depends downwardly in alignment with the handle 42. It will be seen that the operator can grasp the handles 42 and 44, causing the handle to shift to the position indicated in dotted lines in Fig. 5, with the result that simultaneously member 43 and handle 42 engage the stub shafts 35 and 34, causing the roller 27 to shift with respect to the roller 26.

When pressure is released from the handle 42, springs 38 cause roller 27 to shift back to the position indicated in Figs. 4 and 6 and in full line

in Fig. 5, with the two rollers engaging each other. I may also provide means to insure the return of the handle 42 to its proper position, such as spring 45, which is connected to screw 39 at one end and at its opposite end is anchored in rod 41. The tension and adjustment of spring 45 is such as to normally cause handle 42 to return to the position indicated in full lines in Fig. 5. It will be seen that member 43 engages the projecting end of stub shaft or screw 31 preventing the handle from shifting or pivoting beyond this point.

In using my improved copyholder the copy-holding frame 11 is adjusted to the proper height. This is accomplished by releasing thumb screw 15 and shifting rod 16 relative to standard 13. When the device has been adjusted to the proper height, thumb screw 15 is tightened. A manuscript may then be inserted between the rollers 26 and 27. This is accomplished by grasping the handles 42 and 44, placing pressure on the handle 42 until roller 27 has shifted and then inserting the manuscript between the rollers. The handle can then be released so as to permit the roller 27 to return to its normal position and the manuscript can then be fed to the desired position by rotating either one of the handles 36.

If desired I may provide suitable means for supporting the manuscript in upright position, such as the arm 46 pivotally secured to the back 30 of the frame as by means of screw 47. When the arm 46 is employed it can be shifted to vertical position and the manuscript will be supported in the manner indicated in dotted lines at 48 in Fig. 4.

It will be appreciated that the manuscript can be supported at any desired angle by adjusting the frame 11 around its horizontal or vertical pivots. It will also be seen that my device is convenient to operate since it only requires one hand to operate handle 42 to shift roller 27 to spaced relationship with regard to roller 26, leaving the other hand free to insert the manuscript. As the manuscript is copied or read it will have to be fed upwardly from time to time and this can conveniently be accomplished with either the right or left hand by a simple rotation of either one of the handles 36.

If desired I can also provide means for retaining or locking the roller 27 in spaced relationship with regard to the roller 26. Thus in Fig. 7 I have illustrated one type of device that may be employed, in the form of lever 49 pivoted to the end 25 of the frame as by means of screw 50.

The inner end of lever 49 is provided with a hooked portion 51 which is adapted to engage the stub shaft 34 when roller 27 is in shifted position, and a spring 52 is connected between the frame and the hooked end of lever 49 so as to normally hold it out of the path of movement of the stub shaft 34. However, when the hooked end of the lever is depressed to engage the shaft the friction is sufficient to overcome the tension of spring 52 and the lever will effectively prevent the roller from shifting.

In Fig. 7 I have merely illustrated a lever at one end of the frame. It is to be understood of course that a similar lever 49 is preferably provided at the opposite end of the frame so as to similarly engage the stub shaft 35. Where the lever 49 is employed the fixed handle member 44 must be provided with a slotted portion 53 so as to provide clearance for the end of the lever which serves as an operating handle.

In Fig. 8 I have illustrated another type of re-

taining means that may be employed for retaining the rollers in spaced relationship. This means comprises a lever 53 pivotally mounted on the frame as by means of screw 54. The lever 53 is provided with a depending end portion 55 which may be shifted to engage a hooked member 56 formed on the handle 42, when the handle has been shifted to the position indicated in dotted lines in Fig. 8. A coil spring 57 similar to the 10 spring 52 is connected between the frame and the lever to normally hold the lever out of the path of movement of the hooked member 56.

It will thus be seen that I have provided a copyholder which may be employed by stenographers, 15 Linotype operators, public speakers and the like to support a manuscript in a convenient position to be read or copied.

It will also be seen that the copyholder is of relatively simple and inexpensive construction, 20 that it can be readily adjusted to any desired position or angle, that it is convenient to operate and use and has comparatively few moving parts and accordingly is not subject to excessive wear.

It will be understood that modifications may be 25 made in the illustrated and described embodiment of my invention without departing from the invention as set forth in the accompanying claims.

I claim—

1. A copyholder comprising a base, a copyholding frame mounted on said base so as to be adjustable, a pair of rollers mounted in the frame in parallel relationship and in the same horizontal plane when the frame is in horizontal position and adapted to support a manuscript, the angle 35 and height of the manuscript being controlled by adjusting the copyholding frame, and the rear one of said rollers being shiftable with respect to the other roller so as to facilitate insertion of a manuscript between the rollers, means for shifting the first-mentioned roller with respect to the other roller comprising a rod disposed transversely of the copyholding frame parallel to the 40

rollers and positioned substantially above the forward roller and provided with a depending arm engaging a stub shaft projecting at one end of the shifting roller, and a depending operating handle engaging a projecting stub shaft at the other end of the shiftable roller and means including springs engaging the shiftable roller for normally urging the rollers into engagement with each other. 5

2. A copyholder comprising a base having a 10 vertically disposed tubular standard, a rod disposed in the standard and forming telescopic engagement therewith so as to be adjustable both vertically and radially, means for retaining the rod in adjusted position, a copyholding frame 15 connected to the upper end of the rod by means of a horizontally disposed pivot, a pair of horizontally disposed rollers supported for rotary movement in the copyholding frame in substantially parallel relationship and in the same horizontal plane when the frame is in horizontal position, the forward one of said rollers being stationary and the other roller being provided with stub shafts at its opposite ends extending through slots in the copyholding frame so as to be shiftable with respect to the stationary roller, means including a rod parallel to the rollers and positioned substantially above the forward roller mounted on the copyholding frame and extending transversely thereof and provided with a depending arm engageable with a stub shaft at one end of the shiftable roller and having a depending operating handle engageable with the stub shaft at the opposite end of the shiftable roller, operating handles for rotating the rollers, means including springs engageable with the stub shafts on the shiftable roller for normally urging the rollers into engagement with each other, and means including a pivotally mounted lever for releasably retaining the stub shafts in spaced 20 25 30 35 40 relationship. 45

FRANK L. PAUL.
